US0D1002480S

(12) **United States Design Patent** (10) **Patent No.:** **US D1,002,480 S**
(45) **Date of Patent:** **** Oct. 24, 2023**

(54) **WHEEL OR WHEEL COVER**

(71) Applicant: **Daimler AG**, Stuttgart (DE)

(72) Inventors: **Bernhard Hans**, Kirchberg (DE); **Kai Hilpert**, Plochingen (DE)

(73) Assignee: **Mercedes-Benz Group AG**, Stuttgart (DE)

(**) Term: **15 Years**

(21) Appl. No.: **29/810,782**

(22) Filed: **Oct. 8, 2021**

(30) **Foreign Application Priority Data**

Apr. 12, 2021 (DE) 402021201591.8

(57) **CLAIM**

The ornamental design for a wheel or wheel cover, as shown and described.

DESCRIPTION

FIG. 1 is a perspective view of a wheel or wheel cover according to the design; and,

FIG. 2 is a front view thereof.

The broken lines in the drawings illustrate environmental subject matter only and form no part of the claimed design.

1 Claim, 2 Drawing Sheets
